CASE FOR FUEL CONSUMPTION GAUGE

William H. Snow, Chicago, Ill.

Application April 20, 1948, Serial No. 145,830

Term of patent 14 years

(Cl. D52—1)

To all whom it may concern:

Be it known that I, William H. Snow, a citizen of the United States, residing at Chicago, in the county of Cook and State of Illinois, have invented a new, original, and ornamental Design for a Case for Fuel Consumption Gauge, of which the following is a specification, reference being had to the accompanying drawing, forming a part thereof.

In the drawings:

Fig. 1 is a perspective view of a case for fuel consumption gauge, showing my new design, the dial and pointer being illustrated in dotted lines for illustrative purposes;

Fig. 2 is a front elevation, the dial and pointer being illustrated in dotted lines for illustrative purposes; and

Fig. 3 is a side elevation.

I claim:

The ornamental design for a case for fuel consumption gauge, substantially as shown and described.

WILLIAM H. SNOW.
